E. C. NEWCOMB.

CARBURETER.

APPLICATION FILED OCT. 25, 1915.

Patented May 4, 1920.

1,339,218.

Edward C. Newcomb, Inventor
H. C. L. M. Attorney

UNITED STATES PATENT OFFICE.

EDWARD COVERLY NEWCOMB, OF NORTH SCITUATE, MASSACHUSETTS.

CARBURETER.

1,339,218.

Specification of Letters Patent.

Patented May 4, 1920.

Application filed October 25, 1915. Serial No. 57,632.

To all whom it may concern:

Be it known that I, EDWARD COVERLY NEWCOMB, a citizen of the United States, and a resident of North Scituate, in the 5 county of Plymouth and Commonwealth of Massachusetts, have invented certain new and useful Improvements in Carbureters, of which the following is a specification.

My invention relates to an improvement 10 in carbureters of the automatic type, such as is shown in United States Letters Patent Number 1,010,066, issued to me November 28th, 1911, and the object of my present invention is to provide improved mechanism 15 for pulverizing the liquid fuel before it enters the mixing chamber proper of the carbureter. This and the other objects of my invention are more fully explained in the following description, and the essential features 20 of my invention are pointed out in the specification and in the appended claims.

In the accompanying drawings the figure is a vertical section of my improved carbureter.

Similar characters refer to similar parts throughout the accompanying drawings.

Referring now to the embodiment illustrated in the drawing, my carbureter consists of the casing 1, having at its top an 30 outlet for the mixture in the form of a flange-neck tube 2, adapted to be connected to the manifold of the engine. This outlet is controlled by a butterfly throttle valve 3. The casing 1 is opened at its lower end and 35 within this casing is secured a tubular member 6. This member 6 is open at its lower end and is provided in its side walls with a multiplicity of narrow elongated air ports 7. These ports are normally closed by the 40 piston valve 8, which is adapted to be raised by the suction of the engine so as to uncover the ports 7 more or less in accordance with the quantity of mixture demanded by the engine. The weight of the piston valve 8 45 also establishes the vacuum under which the carbureter normally operates. In order to properly control the movements of the piston valve 8 and prevent undue fluttering, it is provided with an upwardly extending 50 closed tubular portion 9 fitted to the interior air port member 6, while the top of the latter member is closed. The fit of the piston in the member 6 being such that the air will be gradually drawn from the space 55 above the piston and cause the piston to rise. In order to permit the piston to fall

promptly and prevent an undue lowering of the vacuum when the demand for mixture is suddenly decreased, I provide a ball check 10 in the top wall thereof. The plug 11, 60 which is cross-shaped in cross-section so as to provide passages 11^a, is driven into the chamber 5, in which the ball 11^b rests to retain the ball in the chamber. The fuel is supplied through a pipe 12 to a float feed 65 chamber 13, where it is maintained at a predetermined level by the float 14 operating the valve 15. From the float feed chamber 13 the liquid fuel is supplied through the passage 16 to the jet 17, the port of 70 which is controlled by the needle valve 18, which is secured to the piston valve 8, the needle valve being so tapered that the proper amount of fuel will be discharged from the jet 17 into the chamber 8^a of the piston 8 75 to properly carburet the air entering the carbureting chamber 1^a through the air ports 7. The fuel which is thus admitted to the chamber 8^a of the piston valve 8 is discharged into the carbureting chamber 1^a 80 through the ports 8^b, where it is pulverized by the streams of rapidly inrushing air entering through the ports 7.

In order to more efficiently pulverize the liquid fuel, I have provided in the base of 85 the valve 8 a multiplicity of air ports 19 which register with the ports 8^b through which the liquid passes from the chamber 8^a through the ports 7 into the carbureting chamber 1^a, and I prefer to construct the 90 ports 19 of lesser diameter than the diameter of the ports 8^b, in order that the air rushing through the ports 19 may be directed into the ports 8^b with sufficient velocity to minutely pulverize the liquid fuel as it 95 passes through the ports 8^b into the carbureting chamber 1^a where it is injected in a finely pulverized condition into the rapidly rushing streams of air entering the carbureting chamber 1^a through the ports 7, 100 which results in still further pulverization of the liquid fuel and an intimate commingling with the air.

21 is an anti-loading tube which is mounted with its lower end just above the 105 bottom wall of the carbureting chamber 1^a, and the upper end discharges into the neck of the carbureter and its purpose is to return liquid fuel which may have condensed on the walls of the carbureting chamber 1^a, 110 to the mixture flowing through the neck of the carbureter above the throttle valve 3.

By means of the passages 22, 23 and 24, communication is established between the carbureting chamber 1^a and the float chamber 13. A pipe 29 is inserted in a neck 26 formed on the cover 13^a of the float chamber 13. The neck 26 is screw-threaded to receive a cap 27, having air inlet passages 28. The tube 29 is inserted in the neck 26 and communication with the outer air is established by means of the passages 28, the tube 26 and the passage 24. The amount of air which may be admitted can be regulated by the adjustment of the cap 27 with reference to the upper end of the tube 29. The 10 spring 30 is for the purpose of taking up the back lash or free movement of the cap upon the threads on the neck 26. The passage 23 is constructed of approximately the same diameter as each of the passages 28, 20 of which there are a multiplicity, usually six or eight. In operation air flows through the passages 28 into the tube 29, through the passages 24, 23, and the tube 22, thereby somewhat reducing the head which acts 25 to force the liquid fuel from the float chamber into the carbureter. 31 is a pointer secured in position by the nut 32. By the regulation of the cap 27 the ratio between the fuel and the air admitted to the carbureter may be varied.

Having described my invention I claim:

1. A carbureter comprising in combination a suction-controlled valve adapted to regulate the flow of air to the carbureting chamber, a chamber in said valve, a member having a fuel discharge port discharging into said chamber in said valve, ports in the side wall of said valve in open communication between said carbureting chamber and said chamber in said valve, and ports for admitting air to said chamber in said valve, said last mentioned ports being arranged to discharge air jets through said first mentioned ports into the carbureting chamber.
2. A carbureter comprising a carbureting chamber, a suction controlled valve adapted to regulate the flow of air to the carbureting chamber, a chamber in said valve, a member having a fuel discharge port discharging into the chamber in said valve, a narrow annular sump in the bottom of the chamber in said valve adapted to collect the fuel discharge into said chamber, ports in open communication between said carbureting chamber and the chamber in said valve and ports arranged to discharge air jets across said sump and through said first mentioned ports into said carbureting chamber.

3. A carbureter comprising a carbureting chamber, a suction controlled valve having a chambered body with ports in its side wall discharging into said carbureting chamber and also having jetting ports in one of its other walls, said latter ports being coaxial with the ports in the side wall and said other wall being spaced from the side wall to form an annular fuel sump and a member having a fuel discharge port discharging into the chamber in the suction controlled valve.

4. A carbureter comprising in combination a tubular member having a multiplicity of air supply ports, a piston valve for controlling said ports, a chamber in said piston valve, a member having a fuel discharge port discharging into said chamber in said piston valve, discharge ports in the walls of the chamber of the piston valve registering with the ports in the tubular member, and means for supplying air to the chamber in the piston valve.

5. A carbureter comprising in combination a tubular member having a multiplicity of air supply ports, a piston valve for controlling said ports, a chamber in said piston valve, a member having a fuel discharge port discharging into said chamber in said piston valve, a multiplicity of discharge ports in the walls of said chamber in said piston valve registering with the ports in the tubular member, and a multiplicity of air supply ports leading into said chamber in the piston valve and registering with said discharge ports in said piston valve.

6. A carbureter comprising in combination a tubular member having a multiplicity of air supply ports, a piston valve for controlling said ports, a chamber in said piston valve, a member having a fuel discharge port discharging into said chamber in said piston valve, a multiplicity of discharge ports in the walls of said chamber in said piston valve registering with said ports in said tubular member, and a multiplicity of air supply ports leading into said chamber in said piston valve and registering with said discharge ports in said piston valve, but of smaller bore than said discharge ports in said piston valve.

Signed at New York city, in the county of New York, and State of New York, this 11th day of October, 1915.

EDWARD COVERLY NEWCOMB.
